UNITED STATES PATENT OFFICE.

ISAAC E. PALMER, OF MIDDLETOWN, CONNECTICUT.

HAMMOCK.

SPECIFICATION forming part of Letters Patent No. 412,892, dated October 15, 1889.

Application filed November 6, 1888. Serial No. 290,137. (No model.)

To all whom it may concern:

Be it known that I, ISAAC E. PALMER, of Middletown, in the county of Middlesex and State of Connecticut, have invented a new 5 and useful Improvement in Hammocks, of which the following is a specification.

I will describe in detail a hammock embodying my improvement, and then point out the novel features in claims.

10 In the accompanying drawings, Figure 1 is a plan view of part of a hammock embodying my improvement, looking from the under side. Fig. 2 is a transverse section of the same on an enlarged scale, taken on the line 15 xx , Fig. 1. Fig. 3 is a plan view of part of a hammock, showing a slight modification. Fig. 4 is a similar view showing another modification. Fig. 5 is an elevation on an enlarged scale and partly broken away of a modified 20 form of a stretcher. Fig. 6 is a similar view of the same, looking from the other side. Fig. 7 is a view of a portion of the joint of the stretcher, detached. Fig. 8 is a transverse section of a pillow and stretcher which may 25 be used. Fig. 9 is a detail view of a pillow which may be used.

Similar letters of reference designate corresponding parts in all the figures.

A designates the body of the hammock, 30 which may be of woven or other suitable material.

B designates the suspending-cords of the hammock, secured in this example of my improvement to warp-threads a .

35 C designates suspending devices to which the suspending-cords are attached and by which the hammock may be hung up.

D designates pockets. These pockets are 40 preferably formed of material of closer texture than the body of the hammock.

In the example of my improvement shown in Figs. 1, 2, and 3 the pockets are secured to the hammock near one of the ends thereof, and their greatest extension is in the direction of the width of the hammock. They are secured to the hammock, as shown, by means of stitching along their side edges and along the ends thereof which are adjacent to the side edges of the body of the hammock.

45 50 Their inner ends are open. In Figs. 1, 2, and 3 the pockets are shown as separated from

each other by a space, but in Fig. 4 they are shown as abutting at their inner ends. In fact, they are illustrated as formed by a single piece of material, an opening h being formed 55 in the material, so as to separate the pockets, and also so as to admit of the introduction of a stretcher D' . In both examples of my improvement the open ends or mouths of the pockets are toward each other. 60

Referring again to Figs. 1 and 2, the stretcher D' is formed of a single piece of metal, which is preferably round and bent near its ends to form enlarged portions or loops b . (Shown more clearly in dotted outline in Fig. 1.) These enlarged or loop portions of the stretcher tend to prevent the latter from breaking through the closed ends of the pockets. The end portions of the stretcher are received within the pockets, and the 70 stretcher is intended to be of such length only that by moving it into one of the pockets to its farthest extent and stretching the hammock the other end portion of the stretcher may be readily slipped into or removed from the other pocket. 75

A stretcher similar to that described may be used with the construction shown in Fig. 4, and I have shown in dotted lines an opening h' , near one side between the pockets, 80 through which the stretcher may be introduced. In this case the opening h (shown on said figure) may be omitted.

E designates re-enforcing pieces. These re-enforcing pieces are preferably made of a 85 strong textile material, and as here shown are in the form of strips and overlap the ends of the pockets near the side edges of the body of the hammock. They are secured about their edges to the hammock by sewing or otherwise, both upon the upper and lower sides of the hammock. It is advantageous to re-enforce the end portions of the pockets, for the reason that the latter are thus rendered more capable of resisting any bursting strain or 90 wear which may be brought upon them by the stretcher.

In Fig. 1 I have shown more clearly a second or supplemental stretcher G , which stretcher is arranged inward of the stretcher 100 D' . The stretcher G is shorter than the stretcher D' , and its end portions are received

in pockets *d*, similar in construction to the pockets *D*, previously described, but arranged farther inward from the side edges of the hammock than are the pockets *D*. By using 5 a second or supplemental stretcher the middle portion of the hammock near the end, forming a support for the head, may be strengthened against sagging where such strength is most required.

10 In Figs. 1 and 2 I have shown a pillow *H* arranged adjacent to the stretchers *D' G*, but upon the opposite side of the hammock, and within a pocket *g* on the hammock. This pillow is shown more clearly in Fig. 9. In 15 fact, a pillow may be used alone or combined with an independent stretcher and be received in the pockets *D*. In this case the pocket *g* might be omitted. I have illustrated such an arrangement of a pillow and stretcher in 20 Figs. 3 and 8. In this example of my improvement the stretcher may be made of wood, and the pillow may be secured to the stretcher by tacking or in any other suitable manner. As the pillow when used alone 25 would operate to stretch the hammock laterally, it would in effect constitute a stretcher.

In Fig. 5 is shown an adjustable stretcher constructed in such manner in this example as to be jointed at about midway in its 30 length. The joint is formed by loops *l* upon the inner ends of portions *l'* of the stretcher, through which loops extend shanks *l''* on securing-pieces *l''*. The shanks *l''* are hollow and abut against each other at their inner 35 ends when they have been passed through the loops from opposite sides of the latter, as shown more clearly in Fig. 6. Upon the securing-pieces *l''* are heads *l⁴*, outside the loops *l*. Through the hollow shanks *l''*, and consequently through the loops *l*, extends a rivet 40 *l⁵*, which rivet passes through suitable apertures in the heads *l⁴*. When the rivet is upset at its ends, the securing-pieces will be secured together. Upon each of the heads *l⁴* of the securing-pieces are oppositely-extending 45 ears or lugs *l⁶*, so arranged that they will contact with each other upon adjacent sides when the securing-pieces have been secured together. The portions *l'*, by means of the 50 loops *l*, may turn freely about upon the shanks *l''* in one direction to fold them together; but when opened out into line they will contact with the lugs *l⁶* to prevent the working of the joint so as to fold the stretcher 55 in the other direction. This form of stretcher is particularly adapted for use with the form of pockets shown in Fig. 4, as it may be folded together in order to be inserted or removed through the opening *h* between the pockets.

What I claim as my invention, and desire 60 to secure by Letters Patent, is—

1. In a hammock, the combination, with a body portion, of two pockets made independent of the hammock and secured upon the face of the body portion of the hammock near 65 one end of the latter and also near opposite side edges thereof, said pockets having their mouths or open ends toward each other and being adapted to receive a stretcher, substantially as specified.

2. In a hammock, the combination, with a body portion, of two pockets made independent of the hammock and secured upon the face of the body portion of the hammock near 70 one end of the latter and also near opposite side edges thereof, said pockets having their mouths or open ends toward each other, and re-enforcing pieces for the pockets at their closed ends, said pockets being adapted to receive a stretcher, substantially as specified. 75

3. In a hammock, the combination, with a body portion, of two pockets made independent of the hammock and secured upon the face of the body portion of the hammock near 80 one end of the latter and also near opposite side edges thereof, said pockets having their mouths or open ends toward each other, and re-enforcing pieces for the pockets at their closed ends, said re-enforcing pieces overlapping the side edges of the hammock and 85 the adjacent ends of the pockets, and said pockets being adapted to receive a stretcher, substantially as specified.

4. In a hammock, the combination, with a body portion, of four pockets made independent of the hammock and secured upon the face of the body portion of the hammock near 90 one end of the latter, two of said pockets being secured to the hammock near opposite side edges thereof and two being secured to 95 the hammock farther inward from the side edges of the hammock than the others and farther from the adjacent end, the pockets of each pair having their mouths or open ends 100 toward each other, said pockets being adapted to receive stretchers, substantially as specified. 105

5. In a hammock, the combination, with a body portion, of two pockets secured thereto near one end thereof and having their mouths or open ends toward each other, and a stretcher made in two sections secured together and adapted to be arranged in said pockets, substantially as specified.

ISAAC E. PALMER.
